UNITED STATES PATENT OFFICE.

HENRY A. KENDALL, OF BALTIMORE, MARYLAND, ASSIGNOR, BY DIRECT AND MESNE ASSIGNMENTS, TO THE EFFICIENCY ENGINEERING COMPANY, OF BALTIMORE, MARYLAND, A CORPORATION OF MARYLAND.

LOCK FOR AUTOMOBILES.

1,345,014.

Specification of Letters Patent. Patented June 29, 1920.

Application filed August 1, 1919. Serial No. 314,613.

To all whom it may concern:

Be it known that I, HENRY A. KENDALL, a citizen of the United States, residing at the city of Baltimore, State of Maryland, have invented certain new and useful Improvements in Locks for Automobiles; and I do hereby declare the following to be a full, clear, and exact description of the invention, such as will enable others skilled in the art to which it appertains to make and use the same.

My invention relates to the construction of locks for automobiles, and especially to that class where clamp members containing or constituting a lock-casing are combined with the steering column and steering post or steering-shaft of the automobile. The invention has for its objects such a simplification and reduction in number of the combining elements or members constituting the clamp and lock casing as will facilitate and cheapen the manufacture and assemblage thereof as well as the application of the clamp members to the steering column, and will also effectively resist the removal of the clamp members from the steering column after application of the same thereto.

To this end the main feature of my invention involves the combination with interlocking clamp members adapted to inclose and bind upon the steering column and having alined openings for the reception of a tubular lock-casing, of a tubular lock-casing adapted to interlock with the clamp members and cause said clamp members to inclose and bind upon the steering column.

A further feature of my invention involves, in conjunction with the above recited combination, the provision on the interior of the tubular lock casing of projections adapted to prevent the withdrawal of the lock from its tubular casing after it has been inserted and finally seated therein, whereby the disassociation of the combining elements is prevented without the application of destructive force.

A further feature of my invention involves the combination with clamp members having alined threaded openings and an externally threaded tubular lock casing, said clamp members and lock-casing having openings for the passage of the lock-bolt, of a bushing adapted to be introduced

through the tubular lock-casing and to constitute a guide and casing for the lock-bolt. 55

There are minor features of invention, all as will hereinafter more fully appear.

In the drawings chosen for the purpose of illustrating my invention, the scope whereof is pointed out in the claims, 60

Figure 1 is a horizontal sectional view of an automobile lock embodying my invention, showing its relation to the steering post and column of an automobile.

Figs. 2 and 3 are detail sectional views of 65 the clamp members.

Fig. 4 is a horizontal sectional view, similar to Fig. 1, but showing the method of inserting the lock-bolt, after the clamp-members have been secured to the steering column. 70

Fig. 5 is a view in side elevation of the tubular lock-casing.

Fig. 6 is a longitudinal central section of 75 the tubular lock-casing.

Fig. 7 is an end view of the tubular lock casing.

Fig. 8 is a side elevation, and end views, of the bushing and lock-bolt guide.

Figs. 9, 10, 11 and 12 are views in end and 80 side elevation of the lock.

Figs. 13 and 14 are sectional views of different forms of clamp members adapted to steering columns of particular cross sections. 85

Like symbols refer to like parts wherever they occur.

In the drawings, S indicates the tubular steering column of an automobile and P the steering post or shaft within the column. 90

The cross section of the steering column S will determine the form or outline of the clamp member, but the form of the clamp members, or general outlines thereof, are matters of selection and adaptation and as such are not involved in my invention. 95

In the principal figures of the drawing the clamp members are shown as adapted to a cylindrical or General Motors steering column; in Fig. 13 as adapted to a Ford steering column, and in Fig. 14 as adapted to a Maxwell steering column. 100

The clamp, which is adapted to inclose and bind upon the steering column to which the lock is to be applied, is composed of a 105 plurality of members 1 and 2 provided with

interlocking lugs 3 and recesses 4, or with equivalent means, for detachably connecting or interlocking the parts, and at the contacting portions opposite thereto with aligned 5 and threaded openings 5 and 6 for receiving an externally threaded lock-casing 7 of tubular form adapted to interlock with the clamp members 1 and 2.

The meeting faces of the clamp members, 10 across the plane of which the tubular lock casing 7 passes, are preferably machined or smoothly finished so that when the clamp members are secured in position on the steering column the line of parting will be indistinct. The tubular lock-casing 7 is preferably threaded on its exterior, as at 8, for a sufficient distance to insure its engaging both 15 of the clamp members as to force them into intimate contact with each other and with the steering column S.

At their meeting points on the interior of the clamp members or the faces in contact with the steering column S, the clamp members are recessed as at 9 to constitute a slot 20 for the passage of the lock-bolt, and opposite thereto the steering column S will be suitably slotted for a like purpose. The steering post P will also be drilled or suitably recessed to receive the lock-bolt.

30 The tubular lock-casing 7, which when the clamp members 1 and 2 are applied to the steering column and are interlocked as at 3 and 4 serves to confine the clamp members and cause them to bind on the steering column, is threaded as at 8 for that purpose and is pierced as at 10 for the passage of the lock-bolt and the reception of a bushing or 35 guide 12 for the lock-bolt.

On the same side and in line with the 40 bolt opening 10 the tubular lock casing 7 is provided on its interior with a plurality of triangularly disposed projections 11 which may be produced by punching the walls of the tubular casing. These projections 45 11 not only engage and prevent the withdrawal of the lock after it has been fully inserted in the lock casing 7 but also prevent the rotation of the lock in the casing.

50 A thimble or bushing 12 of such dimensions that it can be introduced through the tubular casing 7 extends into the opening 10 in the tubular casing, the opening 9 in the clamp members, and the lock-bolt slot in the steering column.

55 L indicates a lock of any well known form adapted for use in the tubular lock casing 7, said lock being provided with a member l and lock-bolt pin p adapted to enter an elongated slot 15 in the end of lock-bolt 13.

The lock-bolt 13 which is to be introduced through the lock-casing 12 after the clamp members 1 and 2 have been secured in place by the lock-casing 7, is preferably eccentrically connected with the member l of the

lock by a link member 14 in which is formed an elongated slot 15 for the reception of the bolt-pin p on the member l; but where conditions will permit the link member 14 may be omitted and the elongated slot 15 may be 70 formed directly on the inner end of lock-bolt 13.

The elemental construction being substantially such as hereinbefore pointed out, the devices will be assembled and applied as 75 follows:

The clamp members 1 and 2 are placed in position around the steering column and interlocked at 3 and 4. The plain portions of the clamp members having the threaded 80 openings 5 and 6 for the reception of the threaded tubular casing member 7 are then brought together with said openings in alignment and are tightly held until the threaded tubular casing member 7 has been 85 inserted and brought into position to engage both clamp members 1 and 2 and turned to bring said members tightly together with the hole 10 in the tubular casing 7 in alignment with the opening 9 through the clamp 90 members 1 and 2. The thimble bushing or guide member 12 is now placed in position. It is, together with the lock-bolt 13, introduced through the lock-casing 7 and forced into position in the openings 9 and 10, by 95 means of a screw driver or any suitable tool. The steering post P is at this time manipulated by means of the usual steering wheel until the lock-bolt can be pushed into the keeper slot in the steering post, after which 100 the lock cylinder L with the key inserted and turned to the locked position is introduced into the tubular casing 7 and pushed down until the pin p engages in the slot of lock-bolt 13.

105 While the lock is held in this position the key is turned to the unlocked position and the steering post is moved to ascertain whether the lock bolt is properly engaged by the pin on the lock member l. If everything is found to operate properly the lock cylinder is pushed to its final position, thus allowing the projections 11 on the interior of the tubular casing 7 to snap into a recess l' or behind a shoulder on the lock cylinder, 110 thereby connecting the several members comprising the automobile lock in a manner preventing disassociation of the combined elements by any force less than a destructive one.

115 I claim:

1. In an automobile lock, the combination with interlocking clamp members adapted to inclose and bind upon a steering column, said clamp members having a lock-bolt opening and openings for the reception of a lock casing, of a tubular lock casing having means for interlocking engagement with said clamp members.

120 2. In an automobile lock the combina- 130

tion with interlocking clamp members provided with a lock-bolt opening and with threaded openings for the reception of a tubular lock casing, of an externally threaded tubular lock-casing for connecting said clamp members and causing them to inclose and bind on a steering post.

3. In an automobile lock, the combination with interlocking clamp - members 10 adapted to inclose and bind on a steering column, said clamp members having a lock-bolt opening and openings for the reception of a tubular lock casing, of a tubular lock-casing having means for interlocking with 15 said clamp members and also having means for interlocking with a lock adapted to be inserted within said tubular lock casing.

4. In an automobile lock, the combination with interlocking clamp members having 20 threaded openings for the reception of a

tubular lock casing, of an externally threaded tubular lock-casing for connecting said clamp members and causing them to inclose and bind on a steering column, said tubular casing having on its interior projections for 25 engaging and retaining an inserted lock.

5. In an automobile lock, the combination with interlocking clamp members having openings for the reception of a tubular lock casing, of a tubular lock casing provided 30 with means for interlocking with the clamp members, said tubular lock casing and clamp members having openings for the passage of a locking bolt, and a thimble or bushing for said lock bolt openings, said bushing being adapted to be introduced through the 35 tubular lock casing.

In testimony whereof I affix my signature.

HENRY A. KENDALL.
